CLAIM

The ornamental design for a glowing christmas tree light, as shown and described.

DESCRIPTION

FIG. 1 is a perspective view of a glowing christmas tree light showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of an alternate position of the glowing christmas tree light thereof;

FIG. 9 is an enlarged view of the selected portion 9 in FIG. 1;

FIG. 10 is an enlarged view of the selected portion 10 in FIG. 1; and,

FIG. 11 is an enlarged view of the selected portion 11 in FIG. 1.

The dashed broken lines show portions of the glowing christmas tree light that form no part of the claimed design. the dot-dash broken lines framing portions of the claimed design are included for the purpose of illustrating enlargements, and form no part of the claimed design.
